CHILD'S MASQUERADE AND PLAY COSTUME

Oliver J. Francis, Baker, Oreg.

Application May 15, 1951, Serial No. 15,185

Term of patent 14 years

(Cl. D3—17)

To all whom it may concern:

Be it known, that I, Oliver J. Francis, a citizen of the United States and a resident of Baker, county of Union, and State of Oregon, have invented a new, original, and ornamental Design for Child's Masquerade and Play Costume, of which the following is a specification, reference being made to the accompanying drawings, forming a part hereof.

In the accompanying drawings:

Fig. 1 is a side view of a child's masquerade and play costume showing my new design; and Fig. 2 is a front view of the same.

I claim:

The ornamental design for a child's masquerade and play costume, as shown.

OLIVER J. FRANCIS.
